OVERHEAD DOOR

Harold F. Collins, Rockford, Ill., assignor to
Howard D. Colman, Rockford, Ill.

Application August 23, 1933, Serial No. 686,340

10 Claims. (Cl. 26—26)

This invention relates to doors of the so-called overhead type in which a plurality of vertically spaced panels or sections are hinged together in edge-to-edge relation and adapted to slide upwardly and around a curved guideway into a horizontal overhead position in opening of the door.

One of the objects of the invention is to provide a new and improved means for locking a door of this type in closed position, which is simple and inexpensive in construction and reliable and durable in operation.

Another object is to provide a novel means for guiding the door so as to reduce to a minimum the amount of head room required.

Other objects and advantages of the invention will become apparent from the following detailed description taken in connection with the accompanying drawings, in which

20 Figure 1 is a fragmentary vertical plan view of a door embodying the present invention looking toward the inside thereof with the door in closed position.

25 Fig. 2 is a fragmentary perspective view of a portion of the door and its locking means.

Fig. 3 is a fragmentary side elevational view of the door in partially open position.

Fig. 4 is a side elevation with the door closed.

The door shown in the drawings comprises generally a plurality of panels 5 pivotally connected at their adjacent edges by hinges 6 and guided at their vertical side edges in channel-shaped rails 7 having a vertical section mounted on the door frame 8 through the medium of a plate 9, a horizontal section secured to or suspended from the ceiling 10 and a curved intermediate section. In the door selected for purposes of illustration, the pintles 11 of the hinges are rigid with laterally projecting cranks 12 which, at their outer ends, carry pins 13 projecting parallel to the hinge axis and supporting rollers 14 which are guided by the flanges 15 and 16 of the rails 7. The free ends of the cranks along each side of the door are connected by links 17 which, as the door approaches closed position, are shifted in a direction to swing all of the cranks into positions perpendicular to the door whereby to move the door bodily against the door frame. Such actuation occurs upon engagement of an extension 18 of the uppermost crank arm 12 with a fixed stop 19.

The invention contemplates the provision, on a door of the general character above described, of a manually operable locking member adapted to engage with a stationary abutment or keeper at

the side of the doorway and located in a position such that it will not be subject to wearing or rubbing action and will not interfere with the movement of the door around the curved portions of the rails 7. To this end, the locking member 5 is so spaced laterally of the rail flanges 15 and 16 that in all positions of the door, the member will be disposed out of contact with these flanges.

In the present instance, two locking members in the form of bolts 20 are employed mounted for 10 movement parallel to the plane of the door in the lateral space between the rear side of the door and the adjacent flanges 16 of the guide rails. In order to space the bolts so that they will be spaced properly from the flanges 16 in all positions of the door, each bolt is mounted closely adjacent the hinge axis between two of the door sections, herein shown extending through apertures and slidably supported by flanges 21 on one of the hinges 6. The cranks 12 are cut away as 20 indicated at 22 to permit location of the bolts in this position. A compression spring 23, coiled around a rod 24 and acting between one of the hinge flanges and a cross-arm 25 which projects into the bolt, constantly urges the latter toward 25 the plate 9. The keeper of the lock comprises a projection 26 rigid with the plate 9 and providing an abutment behind which the bolt is projected by the spring as the door reaches closed position. The upper inclined surface of the projection acts 30 as a cam to move the bolt inwardly as the door approaches closed position.

Retraction of the two bolts to unlock the door is effected in the usual way by turning a handle 27 on the inside or outside of the door. This 35 swings a plate 28 and applies tension to two chains 29 connected at opposite ends to the plate and the respective bolts 20. Normally the plate is held in locking position by a suitable latch mechanism 30 which may be released from the outside of the 40 door by the use of a suitable key.

From an examination of Fig. 3, it will be apparent that the locking bolts 20 are located so 45 remotely from the axes of the adjacent rollers 14 that they will remain out of contact with the adjacent flanges 16 while the hinges on which the bolts are carried are rounding the curved portions of the rails 7. Location of the bolt in this remote position is, it will be observed, facilitated by virtue of the roller crank arrangement employed 50 for producing the desired tight closure of the door, the axes of the rollers 14 being spaced substantially greater distances from the door than the hinge axes.

In order to reduce the amount of head room 55

required for installation of the door, the invention contemplates the provision of independent means for guiding the free edge of the uppermost panel 5 so as to reduce to a minimum the distance to which this edge projects above the horizontal portion of the main rails 7 while the door sections are moving in edge-to-edge relation toward open position. Since only the upper edge of the door is thus guided, the guide may, for economy of manufacture and ease of installation, take the form of a single rail 31 of the same construction as the rails 7 located between the latter and having a straight horizontal portion secured to the ceiling slightly above the rails 7 and a downwardly inclined forward end terminating adjacent the upper edge of the doorway. A roller 32 secured to a bracket 33 on the panel rides between the flanges of the rail 31.

In the initial upward movement of the door out of closed position, the free edge of the upper door panel will be guided away from the door frame along the curved portion of rail 31 and will ride along the horizontal portion as the hinged edges of the other sections round the curved portion of the rail 7 into the horizontal part thereof. Throughout the range of opening movement, the sections 5 remain in edge-to-edge relation with the upper section inclined upwardly slightly while traveling the horizontal portion of the rails. In the final closing movement of the door, the free edge of the upper section rides down the curved part of the rail 31 and thereby moving into place gradually and quietly.

With the independent or supplemental guide above described, it will be apparent that the upper edge of the door is confined in its movements to a path different from but closely adjacent that of the hinged edges of the door. In addition, the upper edge of the door is moved gradually and positively against the door frame without the use of the complicated mechanism which usually must be provided for this purpose in view of the location of the curved portion of the main tracks at the level of the upper part of the doorway.

Where, as in the present instance, the independent guide rail is used with a door embodying torsion counter-balance springs, the drums 34 on which the latter are carried are located beyond the rear ends of the rails 7 and 31 in order to take advantage of the small head room provided for by the auxiliary guide. The spring action is applied to the door through the medium of cables 35 disposed outside of the rails 7 and having one of their ends wound around the drums 34. The opposite ends of the cables are attached to arms 36 secured to the lower edge of the door and bent outwardly around the rails 7. The cables are guided around sheaves 37 mounted on brackets 38 which are supported by and project inwardly from the upper part of the door frame.

The provision of the auxiliary guide for the upper free edge of the door enables the curve portions of the rails to be lowered substantially. To permit of such location and at the same time insure that the door will be raised at least to the level of the upper edge of the doorway, the sheaves 37 are located a substantial distance inwardly from the doorway preferably adjacent the intersection of the horizontal and curved portions of the rails 7. With the sheaves thus located, the faces of the counterbalance springs act along lines spaced rearwardly from the vertical sections of the rails 7 and therefore will raise the door until

the lower edge has been moved substantially clear of the upper edge of the doorway and adjacent the intersection of the curved and horizontal rail sections.

By locating the brackets 38 and the sheaves 37 outwardly from the rails 7 and positioning the auxiliary guide rail 31 intermediate the rails 7, it will be apparent that none of these parts interfere in any way with the movement of the door equipped with locking bolts arranged as above described.

I claim as my invention:

1. The combination of a door having a plurality of panel sections hinged together at their adjacent edges, guide channels at the vertical marginal edges of the door having vertical, horizontal and curved connecting portions, a plurality of crank arms projecting inwardly from the door and each pivoted on the door coincident with one of the hinge axes, rollers projecting from the free ends of said arms into the space between the flanges of said channels, a locking bolt adjacent one of said axes and mounted at one marginal edge of the door for movement in a plane between the door and the vertical portion of one of said channels, said bolt projecting beyond the inner edge of the latter channel and being spaced therefrom a distance sufficient to remain out of contact therewith during movement of the door around said curved portions, and an abutment rigid with the channel and positioned for engagement with said bolt in the closed position of the door whereby to secure the latter against upward displacement.

2. The combination of a door having vertically spaced panels hinged together at adjacent edges, guide channels at the vertical side edges of the door having vertical, horizontal and curved connecting portions, arms projecting laterally from the door at the hinge axes of said sections and having their free ends guided between the flanges of said channels, a stationary abutment disposed outwardly beyond said arms and between the door and one of said channels, and a locking member mounted on the door adjacent one of said hinge axes and normally urged outwardly into the path of said abutment whereby to become engaged behind the abutment and prevent upward displacement of the door, said member projecting beyond the flange of the adjacent channel but being spaced laterally thereof a distance sufficient to remain out of contact therewith while the door travels around the curved portions of said channels.

3. The combination of a door having vertically spaced panels hinged together at adjacent edges, guide channels at the vertical side edges of the door having vertical, horizontal, and curved connecting portions, a locking member mounted on the door adjacent one of the hinge axes and movable into the plane of one of said channels, said member being spaced laterally from the latter channel a distance sufficient to remain out of contact therewith during movement of the door around the curved portions of said channels, and a stationary abutment positioned to be engaged by said member in closed position of the door and acting through the medium of the member to lock the door against upward displacement.

4. The combination of a door having vertically spaced panels hinged together at adjacent edges, guide channels at the vertical side edges of the door having vertical, horizontal and curved connecting portions, a manually controllable locking member mounted on the door closely adjacent one

of the hinge axes thereof and movable endwise into and out of the plane of one of said channels, said member being disposed wholly exteriorly of the latter channel and spaced laterally therefrom 5 so as to remain out of engagement with the side of the channel in all positions of the door, a stationary keeper providing a shoulder behind which said member becomes engaged as the door reaches closed position, and spring means normally urging said member into locking position relative to the door.

5. The combination of a door having vertically spaced panels hinged together at adjacent edges, guide channels at the vertical side edges of the door having vertical, horizontal, and curved connecting portions, a locking member mounted on the door adjacent one of the hinge axes and movable into the plane of the flanges of one of said channels, said member being spaced laterally 10 of the flanges a distance sufficient to remain out of contact with the sides thereof in all positions 15 of the door, and a stationary abutment positioned to be engaged by said member in the closed position of said door and acting to lock the door 20 against upward displacement.

6. A door structure for a vertical doorway comprising, in combination, a plurality of panels arranged in edge-to-edge relation and pivotally connected together at their adjacent edges so as 30 to move as a unit throughout the opening and closing movements of the door, rails at opposite side edges of said door having vertical, horizontal and curved connecting sections guiding the door adjacent its lower edge and the hinged edges of 35 said panels, and a supplemental rail having a horizontal section disposed above and intermediate said first mentioned horizontal sections and acting to guide the free edge of the upper door panel, said supplemental rail having a downwardly extending forward end terminating adjacent the upper edge portion of the doorway and acting on said upper panel to swing the latter 40 against the door frame as the door approaches closed position.

7. A door structure for a vertical doorway comprising, in combination, a plurality of panels arranged in edge-to-edge relation and pivotally connected together at their adjacent edges, rails at opposite side edges of said door having vertical, 50 horizontal and curved connecting sections guiding adjacent the hinged edges of said panels, and a single independent rail for guiding the upper free edge portion of the upper door panel during opening of the door, said last mentioned rail being disposed between and above the level of said horizontal rail sections.

8. A door structure for a vertical doorway comprising in combination, a plurality of panels arranged in horizontal edge-to-edge relation and 60 hinged together at their adjacent edges so as to move as a unit throughout the opening and closing movements of the door, a track comprising rails at opposite sides of the door and having vertical, horizontal and curved connecting 65 sections, rollers supported at the vertical margins of said panels adjacent the hinged edges thereof and offset rearwardly of the door for engaging said rails to guide the door in its movement and to support the same in its open position above.

the upper edge of the door opening, with the hinged edges of the panels disposed in a plane parallel to and spaced substantially above the plane of said horizontal rail sections, an auxiliary track disposed substantially parallel to and spaced 5 above said horizontal rail sections, and means carried by the upper door panel engageable with said auxiliary track for guiding and supporting the free edge of the panel.

9. A door structure for a vertical doorway comprising, in combination, a plurality of panels arranged in horizontal edge-to-edge relation and hinged together at their adjacent edges so as to move as a unit throughout the opening and closing movements of the door, a track 10 comprising rails at opposite sides of the door and having vertical, horizontal and curved connecting 15 sections, rollers supported at the vertical margins of said panels adjacent the hinged edges thereof and offset rearwardly of the door for engaging 20 said rails to guide the door in its movement and to support the same above the upper edge of the door opening in open position with the hinged edges of the panels disposed in a plane parallel to 25 and spaced substantially above the plane of the horizontal rail sections, an auxiliary track comprising horizontal and curved rail sections spaced substantially above the corresponding sections of 30 said first mentioned track, and means carried by the upper door panel and engageable with said auxiliary track for guiding the free edge of the upper panel in the movements of the door, said means cooperating with the curved section of the auxiliary track to align the free edge of the upper door panel in the same vertical plane as the hinged 35 edge of the panel with the door in closed position, and cooperating with the horizontal section of the auxiliary track to support the free edge of the upper door panel in the open position of the door.

10. A door structure for a vertical doorway comprising in combination, a plurality of panels arranged in edge-to-edge relation and hinged together at their adjacent edges, a track comprising rails at opposite side edges of the door having vertical horizontal and curved 45 connecting sections guiding the hinged edges of the door, substantially the entire lengths of said curved sections being disposed below the level of the upper edge of the doorway closed by the door, an auxiliary track including horizontal and 50 curved rail sections disposed substantially above the corresponding rail sections of said first mentioned track for guiding and supporting the free edge of the upper door panel in the movement of the door, counterbalancing means including cables attached to the door adjacent its lower edge and disposed at opposite side edges of the door externally of said vertical rail sections, and sheaves around which said cables extend located 55 intermediate said two tracks and above the level of the upper edge of the doorway substantially rearwardly of said vertical rail sections whereby the lower edge of the door will be moved substantially around said curved rail sections and above 60 the upper edge of the doorway in the opening movement of the door.

HAROLD F. COLLINS.
